UNITED STATES PATENT OFFICE.

LOUIS T. FREDERICK, OF VALPARAISO, INDIANA.

ATTACHMENT FOR CARBURETORS.

Application filed July 23, 1921. Serial No. 487,100.

To all whom it may concern:

Be it known that I, Louis T. FREDERICK, a citizen of the United States, residing at Valparaiso, in the county of Porter and 5 State of Indiana, have invented a new and useful Improvement in Attachments for Carburetors, of which the following is a specification.

This invention relates to attachments for 10 carburetors or fuel mixers of internal combustion engines, and will be fully understood from the following description of a specific embodiment thereof illustrated by the accompanying drawings, in which—

15 Fig. 1 shows the device in side elevation, showing it attached to a carburetor and illustrating its position relative to the exhaust manifold of an internal combustion engine, Fig. 2 is a view taken as indicated 20 by the line 2 of Fig. 1, Fig. 3 is a view taken as indicated by the line 3 of Fig. 1, Fig. 4 is a view of the device in end elevation, Figs. 5 and 6 are views in side elevation of the two 25 halves of the device shown in Fig. 4, viewing said halves in the position they would occupy if opened outwardly as indicated by the arrows, Fig. 7 is a vertical sectional view taken as indicated by the line 7 of Fig. 1, Fig. 8 is a vertical sectional view of the 30 top of the needle valve of the carburetor, showing the manner of attaching my device thereto, and Fig. 9 is a plan view of the top of such needle valve.

As shown in the drawings, 10 indicates 35 the exhaust manifold of an internal combustion engine, and 11 the carburetor thereof. My device comprises primarily a substantially U shaped pipe having a horizontal portion 13 lying adjacent the exhaust manifold 10, a horizontal portion 14 joined to 40 the air inlet 15 of the carburetor 11, and a vertical portion 16 connecting the horizontal portions 13 and 14. The U shaped pipe as a whole I have indicated by the numeral 20. 45 This pipe is formed of two substantially similar halves, each of which is a single casting. The numeral 22 indicates the half 50 glued adjacent the exhaust manifold, and the other half is indicated by the numeral 23. 55 The two halves 22 and 23 are provided with registering bosses or lugs 27 adapted to receive machine screws or bolts 28 for the purpose of holding the two halves together.

The lower end of the pipe as indicated by 60 14 is attached to the air intake of the carburetor 11, and the upper end is supported

in any suitable manner in order to hold the portion 13 adjacent and in close proximity to the exhaust manifold 10. As here shown, such support is accomplished by means of a 65 clip 30 having one end engaged under the nut 31 and the other end fastened by the machine screw 32 into part 23. Additional support is given by attaching a small plate 35 to the part 22 and clamping the same under one end of the bar 36 which is provided for holding the exhaust manifold in place.

The wall of the pipe portion 22 which lies adjacent the exhaust manifold 10 is indicated by 40. This wall is provided with 70 perforations 41, whereby air heated by the manifold 10 may pass from the space between this wall and the manifold to the interior of the pipe and thence to the carburetor 11. By this construction, it will be 75 seen, that the carburetor is supplied with heated air.

The outer portion 23 of the pipe 20 is also provided at its upper end with a hole 45 normally closed by a valve disk 46 held in 80 place by the flat spring 47. The spring 47 has sufficient elasticity to permit the valve disk 46 to be moved inwardly a short distance by atmospheric pressure, thereby opening the hole 45, when the engine is running 85 at high speeds and causing considerable vacuum or rarefaction of air within pipe 20. It will be seen that by this construction, at high engine speeds, some cold air will enter the opening 45 and thus prevent the carburetor 11 from receiving too much hot air.

The upper horizontal part of the pipe portion 23 is also provided with a slanting substantially cylindrical projection 50 adapted to house a bi-metallic thermostatic 90 spiral spring 51 constructed in the ordinary manner from two kinds of metals with different coefficients of expansion in any suitable manner so that an increase in temperature will cause the spring to open or unwind, and vice versa. The lower end of the spring 51 is attached to the casing 50 by the screw 53, and its upper end is fixed to a bushing 54 by the screw 55 which also fixes said bushing to the bar 56. The bar 56 is 100 substantially cylindrical in shape, and extends through a hole in the top of the casing 55. It is provided on its upper end with an enlargement 57. A rod 58 extends through a bore in the bar 56 and is adapted to be 105 adjustably set therein by means of the set screw 60. The bar 58 has its lower end at-

tached by means of the universal joint 61 to the bar 62, the lower end of which is forked as indicated by 63. The prongs of the fork 63 are adapted to engage holes 65 in the adjusting handle 66 on the top of the needle valve of the carburetor 11. This needle valve controls the gasoline jet in the carburetor. By this construction, the parts will so operate, that when the spring 51 becomes heated it will open or unwind, thereby rotating the rods 58 and 62 to close the valve 66. The parts may be adjusted as desired by loosening the set screw 60 rotating the rod 58 to the proper position and then again tightening the set screw 60. In operation of the device, heated air is supplied to the carburetor through the holes 41. After the engine runs a while and the parts become heated, the spring 51 will operate as described above to close the needle valve 66. This is proper, because as internal combustion engine upon starting and when cold requires more gasoline than after the parts become hot. If the engine is speeded up so that considerable rarefaction is caused within the pipe 20, the valve disk 46 will be pressed inward slightly by atmospheric pressure to admit cold air through the opening 45 and thus permit the carburetor from drawing too much heated air, or air that is too hot. Although the present invention has been described in connection with the specific details of a device embodying it, it is not intended that these details shall be regarded as limitations upon the scope of the invention except insofar as included in the accompanying claims.

What I claim as new and desire to secure by Letters Patent is:

40 1. An air heater for carburetors compris-

ing, in combination, a pipe having a closed end portion and openings in a side to admit heated air from the surface of an exhaust manifold, the remaining end of said pipe being open and adapted to be placed in communication with the air inlet of a carburetor, said pipe having a thermostat chamber in its wall opposite said openings and opening to the interior of the pipe, a thermostat in said chamber, means to connect said thermostat with the needle valve of the carburetor for control of supply of liquid fuel to the same, a suction operated cool air intake in the wall of the pipe between its closed end and said chamber, whereby increase of temperature of air drawn through said openings will diminish the rate of fuel supply and whereby the latter effect will be lessened at engine speeds sufficient to open said cool air intake.

2. An air heater for carburetors comprising, in combination, a substantially U shaped pipe formed of longitudinal portions, means to secure said portions together, means to attach said device to an engine, one of said portions having openings adapted to admit heated air from the surface of an exhaust manifold, the other portion having a thermostat chamber opening into the device opposite said openings when the device is assembled, the assembled device having an open end adapted to communicate with the air intake of a carburetor, a thermostat in said chamber and means to connect said thermostat with the fuel needle valve of the carburetor.

In witness whereof I have hereunto set my hand and seal this 18th day of March, 1921.

LOUIS T. FREDERICK. [L.S.]
